(57) **CLAIM**

The ornamental design for a fan motor, as shown and described.

DESCRIPTION

FIG. 1 is a perspective view of a fan motor showing our new design;

FIG. 2 is a top view of the fan motor;

FIG. 3 is a front view of the fan motor;

FIG. 4 is a right side view of the fan motor;

FIG. 5 is a rear view of the fan motor; and,

FIG. 6 is a left side view of the fan motor.

The broken lines shown represent unclaimed subject matter and form no part of the claimed design.
